UNITED STATES PATENT OFFICE

143,703

DESIGN FOR A DOLL OR SIMILAR ARTICLE

Maurice Berkowitz, New York, N. Y.

Application June 4, 1945, Serial No. 119,904

Term of patent 3½ years

(Cl. D34—2)

To all whom it may concern:

Be it known that I, Maurice Berkowitz, a citizen of the United States of America, residing in New York city, county of New York, and State of New York, have invented a new, original, and ornamental Design for a Doll or Similar Article, of which the following is a specification, reference being had to the accompanying drawing, forming part thereof, wherein:

I claim:

The ornamental design for a doll or similar article, substantially as shown.

MAURICE BERKOWITZ.
